United States Patent Office.

CONYERS BUTTON, OF PHILADELPHIA, PENNSYLVANIA.

Design No. 3,392, dated March 2, 1869.

DESIGN FOR A STOCKING-FABRIC.

The Schedule referred to in these Letters Patent and making part of the same.

To all whom it may concern:

Be it known that I, CONYERS BUTTON, of Philadelphia, county of Philadelphia, State of Pennsylvania, have originated a new Design for a Stocking-Fabric; and I do hereby declare that the accompanying drawing, and following explanation thereof, form a full, clear, and exact description of the said design.

In the drawing, the figure represents sufficient of the stocking-fabric to illustrate my design, the prominent features of which are the zigzag stripes A A, each stripe being edged on both sides with a zigzag rib, a.

The body, b, of the fabric is ornamented with rows of loops, arranged in the manner clearly shown in the drawing.

Irrespective of the colors employed in carrying out my design,

I claim the design for a stocking-fabric, substantially as described, and represented in and by the accompanying drawing.

In testimony whereof, I have signed my name to this specification, in the presence of two subscribing witnesses.

CONYERS BUTTON.
